UNITED STATES PATENT OFFICE.

ALLEN W. SMITH AND HENRY McDOWELL, OF NEW YORK, N. Y.

DESIGN FOR A CAP FOR TEETH.

SPECIFICATION forming part of Design No. 29,876, dated December 27, 1898.

Application filed November 30, 1898. Serial No. 697,917. Term of patent 7 years.

To all whom it may concern:

Be it known that we, ALLEN W. SMITH and HENRY McDOWELL, citizens of the United States, residing at the city of New York, (Parkville, borough of Brooklyn,) in the county of Kings and State of New York, have invented and produced a new and original Design for a Cap for Teeth, of which the following is a specification, reference being had to the accompanying drawing, forming a part thereof, in which is represented a perspective view of a cap for teeth embodying the features of our design.

The design consists in a body A of tapering contour, the front of which is defined by an upper concaved surface a and a lower convexed surface a' , while the sides are defined by an upper convexed surface a^2 , from the lower portion of which inclined surfaces a^3 are rearwardly projected, which surfaces meet convexed rear lines a^4 . The back of the cap

simulates a tongue B, the upper portion of which is curved in a rearward direction or away from the upper surface a of the body. The lines b' of the front edge of the tongue 25 below its upper portion are concaved and meet the lower portions of the rear convexed lines a^4 of the body, while the rear lines of the tongue are convexed below the upper portion, as shown at b^3 , said convexed lines b^2 merging into downwardly and forwardly inclined lines b^3 , that connect with the bottom portion 30 of the front convexed section of the body.

We claim—

The design for a cap for teeth herein shown 35 and described.

ALLEN W. SMITH.
HENRY McDOWELL.
